BALING PRESS

David L. Summey, Waterbury, Conn.; The Colonial Trust Company and Richard P. Weeks Summey executors of said David L. Summey, deceased

Application December 4, 1929. Serial No. 411,445

8 Claims. (Cl. 78—42)

This invention relates to presses and to controlling means for presses having a multiplicity of related power actuated elements and more particularly to controlling means for presses of the type generally referred to as baling presses. A preferred embodiment of the invention has been selected for purposes of illustration and will be described herein without mention of other embodiments or adaptations of the invention, which will nevertheless be apparent to those skilled in the art to which this invention relates.

The invention has been developed in connection with presses of heavy construction such as are employed for baling sheet metal trimmings, tangled or rejected metal wire or rods and the like and has been embodied in a specific type of press in which the material placed within the press box is compressed first against a fixed side thereof by one ram, and subsequently further compressed against a removable side by a second ram acting at an angle to and preferably across the face of the first ram after the latter has been brought to the end of its stroke. Therefore the invention will be described particularly with reference to such a construction, it being understood, however, that the invention may be employed with presses of widely different constructions or having entirely different application.

The principal object of this invention is to provide controlling means for a baling press which will render the press largely automatic in its operation so that an unskilled laborer employed to feed the material to be baled will be enabled to operate the press, thereby dispensing with the services of one or more additional skilled operators who would otherwise be required.

Other objects of the invention and certain features of novelty will be apparent from the following description of one specific embodiment of the invention when considered in conjunction with the accompanying drawings in which:

Fig. 1 is a plan view of an installation consisting of a pair of similar associated presses, the cylinder for the cover operating piston being omitted;

Fig. 2 is a side elevation of one of the presses;

Fig. 3 is an elevation looking at the right upper end of Fig. 2;

Fig. 4 is a left end elevation with portions broken away;

Fig. 5 is a left end elevation similar to the lower portion of Fig. 4 but showing certain parts omitted from Fig. 4;

Fig. 6 is a plan view looking upward toward the bottom of Fig. 4;

Fig. 7 is an enlarged plan view of the press box and adjacent related parts;

Fig. 8 is an enlarged side elevation of the press box;

Fig. 9 is a vertical section taken on the line 9—9 of Figs. 7 and 8;

Fig. 10 is a section taken on the line 10—10 of Fig. 1;

Fig. 11 is a side elevation of a pressure limiting device;

Fig. 12 is a front elevation of the same; and

Fig. 13 is a schematic representation of parts together with a wiring diagram for the same.

Two presses are shown in Fig. 1 but the following description will be limited to one press since the other corresponds in all respects to the one described. Referring now to the drawings, particularly Fig. 2, it will be observed that the apparatus comprises a box 20 providing a baling chamber, a movable cover 21 therefor, a horizontal ram 22, and a vertical ram 23.

The horizontal ram 22 is provided with a stem 26 connected by a flange 27 or equivalent structure to a cross head 28 slidable on tie rods 29. The tie rods 29 are rigidly connected at one end to the press box 20 and at the other end to a cylinder block 30 within which a piston 31 for the ram 22 operates under fluid pressure. The stem 32 of the piston 31 may be provided with a flange 33 to connect it with the cross head 28. Likewise the vertical ram 23 is provided with a stem 36 connected by a flange 37 to a cross head 38 slidable on tie rods 39. The tie rods 39 are rigidly connected at one end to the press box 20 and at the other end to a cylinder block 40 within which a piston 41 (Fig. 13) for the ram 23 operates under fluid pressure. The stem 42 of the piston 41 may be provided with a flange 43 to connect it with the cross head 38.

The press box 20 and the cylinder block 30 for the horizontal ram are mounted on horizontal I-beams 50 supported by vertical I-beams or columns 51. The cylinder block 40 for the vertical ram is supported principally by the tie rods 39 but may be kept in position by being secured to

55

the columns 51 if desired. The press is thus seen to be L-shaped in its general configuration. Preferably the vertical ram with its cylinder and related parts, constituting one side of the L is 5 extended below the level of the floor 52 but may be arranged otherwise if desired.

The pistons 31 and 41 for the rams are actuated on their compressing strokes by hydraulic pressure which may be applied to move the pistons forward at will or in a determined order. 10 That is, the pistons are moved forward by what will hereinafter be considered variable or controllable hydraulic pressure. The pistons with their connected rams are returned by what will 15 be hereinafter considered constant hydraulic pressure; that is, pressure of fluid taken directly from the mains and not subject to valve control. Constant return pressure, however, is applied to pistons having smaller area than the pistons employed 20 for compressing and although there will be a constant tendency to withdraw the rams, this tendency will be overcome by the superior force produced by variable pressure acting upon the larger pistons.

25 In the specific embodiment shown the pull-back pistons for the horizontal ram operate within cylinders 55 and are provided with piston rods 56 passing out of the rear ends of the cylinders 55. At their outer ends the piston rods 56 carry 30 yokes 57. Connecting rods 58 passing above and below the cylinder 55 serve to attach the yokes 57 to the cross head 28 connected to the ram 22 and the large piston 31 for actuating the same.

The pull-back pistons for the vertical ram and 35 its piston operate within cylinders 60 and are provided with piston rods 61 connected at their outer ends to yokes 62, which yokes are, in turn, connected with the cross head 38 by connecting rods 63 passing along the sides of the cylinders 40 60.

The cover 21 for the press box 20 is provided with an upstanding lug 65 for connecting the cover with a piston rod 66 operated by a piston moving under fluid pressure within a cylinder 67. 45 Since the power required to move the cover 21 is not as great as that required for the rams it will be convenient to move the cover by pneumatic pressure rather than by hydraulic pressure. Intake pipes 75, 76 are provided at the ends of the 50 cylinder 67 for the admission and exhaust of air under pressure to the cylinder at either side of the piston. The air at both ends will be under variable or controllable pressure whereby the cover may be moved forcibly and quickly in either 55 forward or rearward direction as desired.

The cylinders 55 for the horizontal pull-back pistons and the cylinders 67 for the cover operating piston may be formed integral with or be rigidly attached to the cylinder block 30 and likewise 60 the cylinders 60 for the vertical pull-back pistons may either be formed integral with or rigidly attached to the cylinder block 40.

This invention includes means for controlling the movement of the various elements automatically through a given cycle by a preceding movement of another element and means for interrupting the cycle and allowing the elements to return to their normal positions or to be operated individually by manual controls. While 65 the automatic control means may vary, in the preferred arrangement it will include electrical- 70 ly operated elements and pneumatic elements for the various power units whether the units are pneumatically operated directly or are hydrau-

lically operated but controlled by pneumatic elements acting upon the hydraulic fluid valves.

As shown most clearly in Figs. 1 and 13, a hand operated momentary make switch S1 and a momentary break switch S3 are mounted adjacent the press box 20 within convenient reach of the operator. Normally all the operator is required to do when the box has been filled with material is to press the button of switch S1 and this causes all the elements of the press to move through the proper cycle to compress the material into a bale and elevate the bale above the sides of the box where it may conveniently be removed by the operator, and thereafter to return to their original positions. Switch S3 is for emergency use only. By pressing upon the button of this switch at any time during the compression cycle, the cycle will be broken and the parts will return to their original positions without proceeding through their normal movements.

Referring to Fig. 7, the cover 21 or some part movable therewith is provided with a member 44 for closing a switch S7 shortly after the cover starts forward and holding it closed until the 100 cover is withdrawn. The switch S7 is in circuit with other devices so arranged that the twin press of the pair shown in Fig. 1 cannot be operated while the other is using fluid from the mains. By this arrangement smaller pumps, 105 mains, etc., may be employed than if both presses should be operated simultaneously. Closing of switch S7 also brings about the forward movement of the horizontal ram. The cover or some connected part is also provided with a member 45 110 for closing a switch S9 and holding it closed while the cover is forward. The switch S9 conditions a circuit which later causes the cover to be withdrawn upon the completion of certain other movements.

Referring to Fig. 1, the horizontal ram 22 or some part connected therewith is provided with a member 46 for closing a switch S11 after the ram has approximately completed its forward stroke. The operation of switch S11 causes the 120 upward movement of the vertical ram.

Referring to Fig. 5, the vertical ram 23 or some part connected therewith is provided with a member 47 for operating a switch S15. The switch S15 is normally open but is closed as soon 125 as the vertical ram starts to move upward. It is in circuit with the coil of a relay to cause the coil to be locked in circuit when once put in until the vertical ram withdraws.

The vertical ram likewise is provided with a 130 member 48 for operating a switch S17. Switch S17 is normally open but is closed as soon as the vertical ram starts to move upward. It is in circuit with the switch S9 and another switch S13 presently to be described.

The vertical ram also is provided with a member 49 for operating a switch S5. Switch S5 is normally open but is closed when the vertical ram reaches the extreme upper end of its stroke when moving to eject the bale from the press box 140 after the cover has been pulled back. Operation of switch S5 is the last step leading to the return of all unreturned elements to their original positions.

A switch S13 is actuated by a pressure responsive device generally indicated at 200 whereby the switch is closed when the pressure on the piston of the vertical ram reaches a predetermined amount. As explained above switch S13 is in circuit with switches S17 and S9 and with 145 150

other related devices for causing the withdrawal of the rams and cover after the pressure on the bale reaches the desired point, it being noted that pressure on the vertical ram is relieved 5 slightly before the cover starts to withdraw to prevent damage to the latter.

The movements of the cover operating piston in cylinder 67 are controlled by a magnetically operated valve V8 provided with a coil C8. The 10 supply of pressure fluid to the cylinder 30 for the piston operating the horizontal ram 22 is controlled by a magnetically operated valve V6 provided with a coil C6. While a single magnetic valve is found to operate the horizontal ram 15 satisfactorily for all the present requirements, separate magnetic valves may, if desired, be employed for the inlet and outlet pipes respectively, in a manner similar to that described below for the vertical ram.

20 The inlet of pressure fluid to the cylinder 40 of the piston for operating the vertical ram 23 is controlled by a magnetically operated valve V4 provided with a coil C4 and the outlet of pressure fluid is controlled by a magnetically operated valve V2 provided with a coil C2.

25 The magnetic valves V2, V4, V6, V8 open the conduits which they immediately control when the coils C2, C4, C6, C8 are energized or on and close the conduits when the coils are de-energized 30 or off. This arrangement may be varied if desired but is adopted here for the sake of uniformity and simplicity.

35 Referring now more particularly to the schematic, view, Figure 13, the conduits which the valves V2, V4, V6, V8 immediately control are bypass conduits 71 having their opposite ends opening into cylinders 72 on opposite sides of fluid actuated pistons 73. These pistons 73 operate D-slide valves or equivalent devices 74 controlling the inlet and exhaust of fluid to conduits 75 and 76 opening out of the cylinder 72 adjacent opposite ends.

40 The cylinders are supplied with live fluid through an inlet conduit 69 and the exhaust fluid 45 is conducted from the cylinders 72 by exhaust pipes 77. The area of the pistons 73 on the side adjacent the valve 74 is less than the area of the pistons on the opposite side. One end 71a of the conduit 71 is open to the main chamber of the 50 cylinder 72 containing live fluid at all times and the other end 71b of the conduit 71 opens into the cylinder 72 at the opposite side of the pistons 73. It is therefore evident that when the valve in the conduit 71 is opened, fluid will flow behind the piston and act upon the surface of greater 55 area to move the valve 74, while when the valve controlling the conduit 71 is closed fluid pressure will be exerted only on the side of the piston having the smaller area and the valve 74 will be moved in the opposite direction and be held there. 60 No means for exhausting fluid out of the cylinder adjacent the outer end of the piston 73 is shown but it will be understood that such exhaust means, together with suitable controls 65 therefor, will be provided in practice.

65 As stated above in the case of the cover 20 direct operation of its piston by pneumatic or air pressure is sufficient for the purposes in view. The valve 74 for the cover operating piston will admit 70 fluid through conduits 75, 76 directly to the opposite ends of the cylinder 67.

75 In the case of the rams, however, where high hydraulic pressure is employed, it is more convenient to interpose further means for controlling the flow of hydraulic fluid through the inlet

and outlet conduits thereof. As shown, the pneumatic inlet pipes 75, 76 lead to the opposite ends of cylinders 78 for operating pistons 79 connected to hydraulic control valves 80. The pipes 75, 76 for the horizontal ram are cross connected to 80 opposite ends of the two cylinders employed for inlet and outlet respectively while for the vertical ram the inlets 75, 76 lead only to a single cylinder since, as explained above, separate control valves V4 and V2 are employed for the inlet 85 and outlet conduits respectively.

85 The pneumatic valves 74 and related parts, together with the hydraulic valves 80 and the magnetically operated valves, may all be located adjacent the cylinders to which they are related 90 but preferably the magnetic valves or push button switches for manually controlling them are located at a central station as indicated in Fig. 1 where they may be accessible for manual operation, whereby the units which they control may 95 be operated without regard to the automatic devices. When the valves are so located at a central station, the bypass 71 for each control unit will be elongated sufficiently to extend between the central station and the cylinders 72 to which 100 it is connected at its ends. In Fig. 1 the manual control elements whether they be valve stems or push buttons are referred to by the valve designations.

105 The relative positions of the magnetic valves and the power units which they control may be summarized as follows: When the coil C8 is energized or on the cover moves forward and when the coil C8 is deenergized the cover moves back; when the coil C6 is on the horizontal ram is back 110 but when the coil C6 is off the ram moves forward; when the coil C2 is energized or on, the outlet for high pressure fluid from the cylinder of the vertical ram is closed and, when the coil C2 is off, the outlet is open, and when the coil 115 C4 is on or energized the inlet to the vertical cylinder is closed and when the coil C4 is off the inlet is open.

120 Interposed between the various switches S1, S3, S5, S7, S9, S11, S13, and S17 which may be designated as "primary switches" and the coils C2, C4, C6, C8 of the magnetically operated valves for controlling the movements of the parts of the press are a plurality of relays A, B, C, D, E and F provided with coils CA, CB, CC, CD, CE and 125 CF and with contact members or switches SA, SB, SC, SD, SE and SF. The coils of the magnetically operated valves are in circuit with a source of direct current as, for example, trunks DC1 and DC2. The primary switches and the 130 energizing coils for the relays, however, are in circuit, with a source of alternating current as, for example, trunks AC1 and AC2. The relay switches are adapted to close contacts falling both in direct current circuits and in alternating current 135 circuits.

140 While various types of pressure responsive devices may be employed the present embodiment is that shown in detail in Figs. 11 and 12. A bracket 201 supports a cylinder block 202 and the switch S13. Pressure fluid from cylinder 40 of the vertical ram is admitted to the cylinder chamber 203 formed in block 202 by a pipe 204 so that a piston 205 operating in cylinder chamber 203 is always exposed on its lower surface 145 to the pressure of fluid as it exists in cylinder 40. The piston 205 is provided with a stem 206 extending through a packing bushing 207 to the outside of the cylinder block. The upper end of the stem 206 abuts against and actuates a bar 208 150

slidable upon studs 209 against the action of a coil spring 210 arranged upon a rod 211 integral with bar 208. Tension upon the spring may be adjusted by nuts 213 threaded upon studs 209 on either side of a bar 214 slideable on the studs and the rod 211 and bearing upon the upper end of the spring.

An arm 215 is adjustably mounted on the upper end of rod 211 by nuts 216 and a set screw 217 for actuating a switch lever 218 of the switch S13. When pressure upon the piston 205 reaches a predetermined amount as controlled by adjustment of tension on spring 210 the arm 215 will be caused to actuate switch S13 to relieve pressure upon the piston 41 of the vertical ram as has already been explained. When the vertical ram cylinder and the horizontal ram cylinder are both connected to a common main as will be usual this pressure responsive device will also be instrumental in relieving pressure on the horizontal ram as well as on the vertical ram.

The operation of these various parts will, it is thought, be clearly understood from the following outline of the cycle of operation. A tabulation of circuits involved is included therewith so that it is believed unnecessary to describe the wiring between the various elements separately. The positions of all parts at the beginning of this cycle are as illustrated in Fig. 13. From this it may be observed that the cover and rams are fully retracted; that primary switches S1, S5, S7, S9, S11, S13, S15, S17 are open while S3 is closed; that solenoid coils V2, V4, V8 are off while V6 is on; and that relay switches SA, SB, SC, SD, SE, SF and SFF (for the parallel press) are all down.

The normal cycle set up by pressing the button of manual control switch S1 is:

I. STARTING SWITCH S1 CLOSED

- (A) SA pulled up (circuit AC1, 104, 103, S1, 101, CA, 102, AC2)
 40 1. SA locked up (circuit AC1, 104, S3, 112, SD, 111, SA, 110, CA, 102, AC2)
 45 2. C8 on (circuit AC1, 106, SA, 107, C8, 108, DC2)—cover moves forward
 3. One gap in circuit of CB closed (conductors 114, 122 at SA)

II. COVER MOVES FORWARD

- (A) S9 closed, bridging one gap in circuit of CD (conductors 161, 162)
 50 (B) S7 closed
 1. SF raised (circuit AC1, 116, S7, 115, SFF, 123, CF, 117, AC2)
 55 (a) Two leads (120, 121) to twin press opened making it impossible to apply hydraulic pressure on that press while this press is operating.
 (b) The normally open inlet valve 80 for the vertical ram of the twin press is closed to prevent wastage of fluid there in order that pressure may be built up here. This is done by energizing CC4 for VV4 of the twin press (circuit, DC1, 153, SF, 155, CC4, DC2)
 60 A similar result is provided when the twin press is operating by energizing V4 through circuit, DC1, 167, SFF, 168, C4, 145, DC2.

- (c) SB pulled up (circuit AC1, 116, S7, 115, SFF, 123, SF, 114, SA, 122, CB, 124, AC2)
 70 1'. C6 off (circuit DC1, 127, SB, 128, C6, 129, 108, DC2 broken at SB)—horizontal ram moves forward.

2'. C4 on (circuit DC1, 131, SB, 132, 135, SC, 142, 143, 144, C4, 145, DC2)—vertical inlet valve 80 closed.

III. HORIZONTAL RAM MOVES FORWARD

- (A) S11 closed
 1. SC pulled up (circuit AC1, 138, S11, 139, CC, 140, AC2)
 (a) SC locked up (circuit AC1, 154, SE, 152, SC, 151, CC, 140, AC2)
 (b) C4 off (circuit broken at 135, SC, 142)—vertical inlet valve open
 (c) C2 on (circuit DC1, 146, SC, 147, SD, 148, C2, 149, 145, DC2)—vertical outlet valve closed

IV. VERTICAL RAM MOVES UP

- (A) S15 closed
 1. One gap in lock circuit of CE bridged (conductors 157, 158)
 2. SF locked up (circuit, AC1, 158, S15, 119, SF, 118, CF, 117, AC2)
 (B) S17 closed
 1. Second gap of CD bridged (conductors 159, 160)

V. PRESSURE REACHES 1600 POUNDS ON GAUGE, completing the compressing cycle.

- (A) S13 closed
 1. Last gap closed in make circuit of CD to raise SD (circuit AC1, 161, S9, 162, S13, 159, S17, 160, CD, 163, AC2)
 (a) SD locked up beyond control of S13, S17 (circuit AC1, 161, S9, 162, 166, SD, 165, CD, 163, AC2)
 (b) C2 off—vertical outlet valve opened (circuit broken by raising of SD)
 (c) C4 on—vertical inlet valve closed (circuit DC1, 131, 133, SD, 134, 132, 136, SD, 137, 143, 144, C4, 145, DC2)

- 1'. Pressure drops, S13 opened (conductors 159, 162)
 (d) SA dropped (circuit broken at 112, 111 by raising of SD)

- 1'. Gap in lock circuit CA opened (conductors 110, 111)
 2'. C8 off—cover moved back (circuit broken at 106, 107 by dropping of SA)
 3'. SB dropped (circuit broken at 114, 122 by dropping of SA)
 (a') C6 on— inlet valve closed and outlet valve opened—horizontal ram moved back under constant pressure in pull-back cylinders 55 (circuit DC1, 127, SB, 128, C6, 129, 108, DC2)

VI. COVER MOVES BACK

- 135 (A) S7 opened making another gap in circuit of CB (conductors 115, 116)
 (B) S9 opened
 1. SD dropped (circuit broken at 161, 162 by opening of S9)
 (a) Gap in lock circuit CD opened (conductors 165, 166)
 (b) C2 on—vertical outlet valve closed (circuit DC1, 146, SC, 147, SD, 148, C2, 149, 145, DC2)
 (c) C4 off—vertical inlet valve opened (circuit broken at 133, 134 and also at 136, 137 by dropping of SD)

150

- VII. HORIZONTAL RAM MOVES BACK
 (A) S11 opened making gap in make circuit of CC (conductors 138, 139)
- VIII. VERTICAL RAM MOVES FULLY UP to lift bale out of box.
 5 (A) S5 closed
 1. SE raised (circuit AC1, 170, S5, 171, CE, 172, AC2)
 (a) SE locked up (circuit AC1, 158, S15, 10 157, SE, 175, CE, 172, AC2)
 (b) C4 on—vertical inlet valve closed (circuit DC1, 176, SE, 177, 144, C4, 145, DC2)
 (c) SC dropped (circuit at 154, 152 broken 15 by raising of SE)
 1'. Gap in lock circuit CC opened (conductors 151, 152)
 2'. C2 off—vertical outlet valve opened—(circuit broken at 147, 148 by dropping 20 of SD)
- IX. VERTICAL RAM MOVES DOWN
 (A) S5 opened making one gap in make circuit of CE (conductors 170, 171)
 (B) S15 opened
 25 1. SE dropped (circuit broken at 158, 157 by opening of S15)
 (a) Another gap in lock circuit of CE opened (conductors 157, 175)
 (b) C4 off—vertical inlet valve opened (circuit broken at 176, 177 by dropping 30 of SE)
 (c) Gap in lock circuit of CC closed (conductors 152, 154)
 2. SF dropped (circuit broken at 119, 158 by opening of S15)
 (a) Gap in lock circuit of CF opened (conductors 118, 119)
 (b) Circuit to twin press closed making it possible to operate that press (conductors 120, 121)
 40 (c) Another gap in circuit of CB opened (conductors 114, 123)
 (C) S17 broken, opening another gap in make circuit of CD (S13 and S9 already open in its circuit) (conductors 159, 160)
- Should anything happen to make it necessary or desirable to interrupt the normal operation of the press after the cycle has been initiated, this may be done by pressing the button to open switch S3 which is located near S1. Opening of switch S3 50 breaks the lock circuit of the coil CA of relay A to drop SA. The circuit involved is AC1, 104, S3, 112, SD, 111, SA, 110, CA, 102, AC2. Relay A may be considered as the master control element of 55 the apparatus and its deenergization causes the return of all parts to their original or normal off positions at any stage of the compressing cycle. A detailed recital of the movements following the deenergization of relay A would be rather involved if every possible situation, i. e., the interruption of normal operation at any and every stage of movement throughout the cycle, were discussed and this recital it is believed may be 60 excused since a consideration of the circuit diagram and the above outline of the normal cycle should furnish an understanding of movements occurring after interruption.
- As hereinbefore stated the solenoid operated 70 valves controlling the by-pass conduits 71 are preferably located where they may be operated manually. For this purpose the stems of the valves are made to extend beyond their actuating coils so as to be readily accessible. Since the 75 control of fluid in conduits 71 is sufficient to cause movement of the power units without regard to the automatic control devices it is obvious that the power units may be actuated individually out of turn either at any time during the cycle or at any other time.
- I desire it to be understood that the present invention is susceptible of various embodiments other than that disclosed above and that it is not to be limited except as specified in the claims.
- What I claim is:
1. In a baling press or the like, in combination, means providing a material receiving chamber, a fluid pressure operated cover movable to close one side of the chamber, a fluid pressure operated ram movable into said chamber, a second fluid pressure operated ram movable into said chamber across the face of said first mentioned ram, means controlled by the movement of said cover and said first mentioned ram to cause said second mentioned ram to be actuated only after the cover and first ram have moved forward, means including a pressure responsive device for relieving pressure upon said rams at a predetermined point and permitting withdrawal of said rams and said cover, means controlled by movement of the cover for thereafter effecting re-application of pressure upon said second ram to cause it to eject the bale from the chamber, and means controlled by movement of said second ram upon its bale ejecting stroke for causing all unreturned elements to return to their original positions of rest. 90
2. In a baling press or the like, in combination, means providing a material receiving chamber, a fluid pressure operated cover movable to close one side of the chamber, a fluid pressure operated ram movable into said chamber, a second fluid pressure operated ram movable into said chamber across the face of said first mentioned ram, means controlled by the movement of said cover and said first mentioned ram to cause said second mentioned ram to be actuated only after the cover and first ram have moved forward, means including a pressure responsive device for relieving pressure upon said rams at a predetermined point and permitting withdrawal of said rams and said cover, and means including a switch operated by said cover and parts controlled by said switch for thereafter effecting re-application of pressure upon said second ram to cause it to eject the bale from the chamber. 105
3. In a baling press or the like, in combination, means providing a material receiving chamber, a power operated cover movable over one side of said chamber, a plurality of power operated rams movable into said chamber, a pressure responsive device for limiting the pressure of said rams upon a bale of material in said chamber, manually controlled means for initiating a cycle of operation of said power operated elements, interlocking means associated with and controlled by the movement 110 of said elements which causes coordinated movement of all of them to compress and eject a bale and to return to their initial positions, manually controlled supervisory means for interrupting the cycle at any time during the compression cycle, 115 and means controlled by the action of said supervisory means for returning the parts to initial positions upon such interruption. 120
4. In a baling press or the like, in combination, means providing a material receiving chamber, a power operated cover movable over one side of said chamber, a power operated ram movable into said chamber from one direction, a second power operated ram movable into said chamber in a direction transverse to the first, 125 130 135 140 145 150

- and interlocking means associated with and controlled in accordance with the movements of said power operated elements which causes co-ordinated movement of all of them to compress and eject a bale and to return them to their original positions by the initial operation of a single control element at the beginning of a cycle, said means including electromagnetic re-lays, switches operated by said cover and rams governing the relays, and electromagnetically operated power regulating devices governed by said relays controlling the movements of said cover and rams in coordination to the completion of the cycle. 80
5. In a baling press or the like, in combination, means providing a material receiving chamber, a fluid pressure operated cover movable to close one side of the chamber, a fluid pressure operated ram movable into said chamber, a second fluid pressure operated ram movable into said chamber across the face of said first mentioned ram, means controlled by the movement of said cover and said first mentioned ram which causes said second mentioned ram to be actuated only after the cover and first ram have moved forward, means including a pressure responsive device for relieving pressure upon said rams and cover at a predetermined point, and means controlled by the pressure responsive device for causing withdrawal of said rams and said cover. 90
6. In a baling press or the like, in combination, means providing a material receiving chamber, a power operated cover movable to close one side of the chamber, a pressure fluid operated ram movable into the chamber, a pressure responsive device associated with said ram for relieving pressure thereupon at a predetermined point while a bale is being compressed, means actuated by said pressure responsive device for caus- 100
7. In a baling press or the like, in combination, means providing a material receiving chamber, a power operated cover movable to close one side of the chamber, a power operated ram movable into the chamber while the cover is closed to compress a bale of material and subsequently being further movable when said cover is removed to eject the bale, means responsive to the closing movement of said cover for advancing said ram, means responsive to the pressure on the ram for retracting the ram, and means responsive to the opening movement of said cover for again advancing the ram to eject the bale. 105
8. In a baling press or the like, in combination, means providing a material receiving chamber, a plurality of power operated rams for said chamber, one of said rams being movable transversely of another of said rams, and interlocking means associated with said rams and responsive to the movements thereof which mutually control without the necessity of manual intercession after the cycle of operations has been initiated the movement of one by movement of another and vice versa until the cycle of operations has been completed, said rams each being operated by a fluid pressure device, and said controlling means comprising an electromagnetic valve for controlling the flow of fluid to each of said devices and an electrical circuit including a switch operated by movement of one of said rams for controlling the valve and through it the operation of another of said rams. 110
